**PIVOTED POWER UNIT FOR PORTABLE
WASTE DISPOSER**

Bernard J. Brezosky, Louisville, Ky., assignor to General Electric Company, a corporation of New York
Filed Apr. 17, 1964, Ser. No. 360,608
7 Claims. (Cl. 241—46)

This invention relates to portable waste disposers and, more particularly, to such waste disposers having pivoted power units.

Portable waste disposers have been made to be mounted in kitchen sinks in position to discharge the comminuted waste into the sink drain opening. Such disposers utilize a two-part apparatus including a hopper, having a comminuting means, and a power unit for driving the comminuting means. In prior art devices the power unit was separable from the hopper and was removed to expose an access opening in the top of the hopper for insertion of waste material. When removed from the hopper, the power units were quite often placed on kitchen counters or other surfaces while the user inserted waste material into the hopper. With such arrangements the power units could be easily knocked from the cabinets or dropped by the user and broken.

It is an object of this invention to provide a portable waste disposer in which the access opening is made available without removing the power unit.

It is another object of this invention to provide a portable waste disposer in which the power unit is movable on the hopper unit between a waste material loading position and a driving position.

Briefly stated in accordance with one embodiment of this invention, a waste disposer is provided which includes a hopper provided with an access opening in the upper wall of the hopper through which waste material and water are supplied to the hopper. Comminuting means are mounted within the hopper and include a shaft extending upwardly in alignment with the access opening. A power unit, including an electric motor, is mounted on the hopper to drive the comminuting means. A drive shaft is mounted adjacent one edge of the power unit and drivingly connects the top of the comminuting shaft to the rotor shaft of the motor through a gear train. The power unit is normally mounted in registry with the access opening in the hopper so that the electric motor may drive the comminuting shaft. The power unit is pivotable about the connection between the comminuting shaft and the drive shaft to move out of registry with the access opening and over a solid portion of the upper wall of the hopper to expose the access opening for insertion of waste material.

For a more complete understanding of this invention reference may be had to the accompanying drawings in which:

FIGURE 1 is an elevational view of a portable waste disposer embodying one form of this invention, the view being partly broken away and partly in section for purposes of illustration;

FIGURE 2 is a plan view of the hopper unit of the embodiment of FIGURE 1;

FIGURE 3 is an elevational view similar to FIGURE 1 illustrating a second embodiment of this invention, partly broken away and partly in section to illustrate details;

FIGURE 4 is a plan view of the embodiment of FIGURE 3;

FIGURE 5 is a partial elevational view of still another embodiment of this invention, partly broken away and partly in section for purposes of illustration; and

FIGURE 6 is a plan view of a portable waste disposer illustrating another embodiment of this invention.

2

Referring to FIGURES 1 and 2, there is shown a food waste disposer comprising separable units 10 and 11, the unit 10 constituting a hopper enclosing a comminuting means while the unit 11 constitutes a power unit for driving the comminuting means. The hopper 10 is defined by a generally upright side wall 12, a bottom wall 13, and an upper wall 14. The bottom wall 13 is preferably cup-shaped, being provided with an upright side wall portion 15 which is nested within the lower part 5 of side wall 12 and is positioned with respect to side wall 12 by an inner circular ridge 16 formed on the inside of the side wall 12. Mounted around the outside of the side wall 12 is a combined bumper and decorative ring 17 formed of a resilient material such as rubber. The walls 12 and 13 may be secured together in any 10 suitable way as by bonding or gluing, and ring 17 may be assembled merely by "snapping" it in place.

The comminuting means is mounted within bottom wall 13. The comminuting means comprises a stationary 20 shredding ring 18 which is provided with cutting surfaces 19 and a series of lower and upper apertures 20 and 21. The shredding ring is provided with an out-turned flange 22 sandwiched between the lower surface of ridge 16 and a seat provided in the upper edge of side wall portion 15 25 of bottom wall 13. The flange 22 is surrounded by a resilient gasket 23 to make the joint fluid tight. Co-acting with the shredding ring is a rotatable flywheel 24 which is provided with a pair of impellers 25 arranged so that when the flywheel is rotated they impel waste material against the shredding ring 18 to comminute the material to a fine mass. During this operation water is caused 30 to flow into the hopper. The water and comminuted material flow through the apertures 20 and 21 and into an annular drain space 26 provided between ring 18 and wall portion 15, and thence downwardly into a drain chamber 27 under the flywheel 24. The drain chamber 27 drains through openings 28 into the drain line of the sink (not shown).

In order to mount the disposer in the sink and to guide 40 the comminuted material from the openings 28 into the drain line, the bottom wall 13 is provided with a circular resilient gasket 29, which has a diameter sufficiently large that it will encompass any sink opening with which the apparatus normally will be associated.

The flywheel 24 is supported and driven by a driving 45 shaft 30. This shaft is journaled in a bearing 31 provided in the central axis of the bottom wall 13. Preferably the central area 32 of the flywheel is dished downwardly and constitutes an upper thrust bearing for the flywheel while the lower end of the shaft is provided with a head 33 which constitutes a lower thrust bearing. A flywheel retainer 32a is threaded on the shaft 30 and received in the dished area 32 of the flywheel to lock the flywheel to the shaft. The positioning of the flywheel is 55 accomplished by the shoulder 34 cut on shaft 30.

A comminuting chamber 35 above the flywheel is defined by the inner circular ridge 16 and the upper wall 14. The upper wall 14 seats upon the upper edge of side wall 12 and is secured thereto in any suitable way 60 as by bonding or gluing. The upper wall 14 includes a generally flat plate portion 36 which closes the top of side wall 12 and defines an access opening 37 for the introduction of waste material and water into the hopper 19 and thence into the comminuting chamber 35 above the flywheel 24. To prevent the waste material and water from splashing outwardly the upper wall 14 is provided 65 with an outer upturned peripheral flange 38.

The opening 37 is provided adjacent one side of the top wall 14 and a portion of the top wall between the 70 opening 37 and flange 38 is sloped downwardly, as at 39, to guide waste material into the hopper. The driving shaft 30 extends vertically upward through the hopper

and into alignment with the inner portion of opening 37. The shaft is driven by the power unit 11.

The power unit includes a motor casing 40 and an interfitting gear housing 41 which together form the casing or housing for the power unit. An electric motor 42, having a stator 43 and a rotor 44, is mounted in the motor casing. The rotor 44 is mounted to rotate on a vertical axis on a rotor shaft 45 which is received in a bearing 46 mounted in gear housing 41. A rubber diaphragm 41a is mounted between the gear housing 41 and motor casing 40 and extends inwardly into engagement with rotor shaft 45.

A drive shaft 47 is mounted in a bearing 48 adjacent the edge of gear housing 41. Rotor shaft 45 is provided with a gear 49 and drive shaft 47 is provided with a gear 50 which is connected to gear 49 through an intermediate gear 51. The gear 51 is mounted on a shaft 52 received within a bearing 53. Drive shaft 47 extends downwardly through a recess 54 provided in gear housing 41, the recess being closed by a lip seal 54a. Drive shaft 47 is provided with a hexagonal lower end 55 which is received in a complementary socket 56 formed in the upper end of the driving shaft 30. Thus the rotor 44 is connected to the driving shaft 30 through the rotor shaft 45, gear 49, gear 51, gear 50 and drive shaft 47. When electric power is provided to the motor, the driving shaft 30 will be rotated, thereby rotating shaft 30 and flywheel 24 so that impellers 25 may comminute any material contained within comminuting chamber 35.

In order to move power unit 11 out of registry with opening 37 so that waste material may be inserted into hopper 10 the motor casing 40 is provided with a handle 57. When it is desired to move the power unit the user grasps handle 57 and pivots the power unit about driving shaft 30 and drive shaft 47 in the counterclockwise direction (as viewed from top of the disposer). As the power unit 11 pivots around the drive shaft it substantially uncovers access opening 37 so that waste material may be inserted into the hopper. When the user desires to dispose of the waste material the power unit is merely pivoted in the clockwise direction until it is in registry with access opening 37 and electric power is then supplied to motor 42.

In order to provide for the pivoting movement of the power unit the flat plate portion 36 of upper wall 14 is provided with an arcuate recess 58 (best seen in FIGURE 2), one end of which forms the upper edge of access opening 37. The dashed lines 59 and 60, in FIGURE 2, show the two extreme positions of the outer periphery of power unit 11, the line 59 showing the comminuting or grinding position and the line 60 showing the loading position. Thus it will be seen that when the power unit 11 is pivoted in the counterclockwise direction to uncover the access opening 37 it does not uncover the entire opening since it pivots about driving shaft 30 which is in alignment with a portion of opening 37. When electric power is provided to motor 42 the direction of rotation of rotor 44 is such as to cause the power unit 11 to attempt to precess in the clockwise direction; however, gear housing 41 engages the edge of arcuate recess 58 and retains the power unit in registry with access opening 37.

Referring now to FIGURES 3 and 4 there is shown another embodiment of the invention. This embodiment includes a hopper 10' and a cooperating power unit 11'. The hopper of FIGURE 3 is substantially the same as the hopper of FIGURE 1, including a side wall 12, a bottom wall 13 and circular resilient gasket 29. An upper wall 61 seats on the upper edge of the side wall 12 and is secured to it in any suitable way as by bonding or gluing. The upper wall includes a plate portion 62 extending inwardly and downwardly in the top of the hopper in a generally funnel-like form. The inner edge of the plate portion 62 defines a relatively large opening 63. This opening 63 constitutes an access opening for an introduction of waste material and water into the

hopper and the comminuting chamber 35. To prevent water and waste material from splashing outwardly, the upper wall is provided with an outer, upturned peripheral flange 64.

5 The shaft 30 extends vertically upwardly through the hopper and into opening 63. This shaft is driven by the power unit 11'. The power unit includes a cylindrical motor casing 65 enclosing a motor (not shown) having a rotor (not shown) mounted to rotate on a vertical axis. The rotor drives a rotor shaft 66 which, in turn, drives an output drive shaft 67 through a gear reduction train comprising gears 68, 69, 70 and 71, the latter being formed as a part of the output drive shaft 67. A gear housing 72 is attached to the lower end of motor casing 65 and houses the reduction gear train and journals the output drive shaft 67. The gear housing has a body portion 73 of a slightly smaller diameter than the lower end of motor casing 65 and a lower flange 74 having a larger diameter than the body portion 73. The gear housing 72 and motor casing 65 together form an integral casing for power unit 11'.

Power unit 11' is arranged to seat in an operating position in registry with access opening 63, in which position a driving connection is automatically effected between output drive shaft 67 and driving shaft 30 to rotate the flywheel. This connection is accomplished by the hexagonal upper end of driving shaft 30 which is received in a complementary shaped socket 75 formed in the output drive shaft 67. The socket 75 is somewhat larger than hexagonal end 55 in order to provide for misalignment between the axes of shafts 67 and 30 within narrow limits.

For moving the power unit 11' into and out of registry with access opening 63 a collar 76 is provided around the 35 smaller diameter body portion 73 of gear housing 72 so that the gear housing may slide within the collar with the lower end of motor casing 65 and the flange 74 serving as stops. The collar 76 is formed with a hinge member 77 which is connected by a pin 78 to a similar hinge member 79 formed in upper wall 61 so that the collar 76 will pivot about hinge member 79. A housing 80 is positioned on the upper wall 61 opposite hinge member 78 and encloses a manually operable latch member 81. A spring 82 is mounted within the housing 80 and biases the latch member toward the collar 76, which is formed with a recess 83 to receive the end of latch member 81. This forms a latching arrangement to hold power unit 11' in registry with access opening 63.

When it is desired to move the power unit 11' from the operating position (shown in FIGURE 3), the latch member 81 is manually moved against spring 82 to retract it from recess 83, then the power unit 11' is pulled longitudinally upwardly within collar 76 until flange 74 engages the collar. At this point shaft 67 has been disconnected from shaft 30 and the power unit 11' may be provided in a clockwise direction about hinge member 79 to uncover access opening 63. When it is desired to operate the disposer, power unit 11', including collar 76 is pivoted in a counterclockwise direction about hinge member 79 until recess 83 in collar 76 engages latch member 81. Power unit 11' then is moved downwardly within collar 76 until the lower end of the motor casing 65 engages the collar. At this point hexagonal end 55 of driving shaft 30 engages socket 75 of drive shaft 67, properly connecting power unit 11' to the flywheel for comminuting waste material.

Referring now to FIGURE 5 there is shown a modified latching arrangement for use with the embodiment of FIGURES 3 and 4. A housing 84 is provided along one portion of motor casing 65 and includes a longitudinal recess 85. An elongated, resilient arm 86 is mounted in the recess 85 and its upper end is received in push button 87. The lower end of arm 86 is formed into a tab 88 which projects through an opening 89 in the outer wall 75 of housing 84 and engages a hook portion 90 formed on

the plate portion 62 on the upper wall 61. Adjacent push button 87 arm 86 is formed into a spring 91 which is mounted between a shoulder 92 formed in housing 84 and push button 87 to bias the arm to its upper position so that tab 88 engages hook portion 90. When it is desired to remove the power unit from registry with opening 63 push button 87 is depressed; this moves tab 88 downwardly so that it is cammed inwardly by the edge 93 of housing 84 engaging the angled portion 88a of tab 88. The tab 88 is thereby removed from engagement with hook portion 90 and the power unit is released for vertical movement.

Referring now to FIGURE 6 there is shown another embodiment of this invention in which the hopper unit is similar to that shown in FIGURES 3 and 4. The changes involve a modified arrangement for mounting the power unit 11' for pivotal movement. The collar 76', which is mounted about the gear housing, is formed with a horizontally extending ear 93 having a vertical opening 94 therethrough. A stud 95 extends through the opening 94 and is mounted in plate portion 62' of upper wall 61'. The plate portion 62' is formed with an arcuate recess 96 one end of which intersects the access opening through plate portion 62'. Thus, when it is desired to move power unit 11' out of registry with the access opening the latch member 81 is removed from a recess 83' formed in collar 76'. Then the power unit is lifted vertically within the collar and pivoted about stud 95 in the clockwise direction, the lower end of the power unit being received in recess 96. When it is desired to return the power unit into registry with the access opening in plate portion 62', the power unit is rotated about stud 95 until latch member 81 engages in slot 83' in collar 76', then the motor casing 65 and gear housing 72 are moved longitudinally downwardly within collar 76' until the lower end of motor casing 65 engages the collar.

It may be desirable under certain circumstances to provide means to allow rotation of the power unit within either collar 76 or collar 76' to overcome possible angular misalignment between the hexagonal end 55 and the hexagonal socket 56. This is not absolutely necessary, however, since one may manually rotate shaft 30 to align end 55 and socket 56 prior to pivoting the power unit toward engagement with the comminuting means.

Although I have shown and described specific embodiments of my invention, I do not desire my invention to be limited to the particular constructions shown, and I intend by the appended claims to cover all modifications within the true spirit and scope of my invention.

What I claim as new and desire to secure by Letters Patent of the United States is:

1. A portable waste disposer for use in a kitchen sink comprising:

- (a) a housing forming a hopper,
- (b) said housing including a wall defining an access opening for receiving waste material, said opening being positioned adjacent one edge of said upper wall, said upper wall further defining a recess communicating with said access opening,
- (c) waste material comminuting means within said hopper including a rotatable impeller having a first drive shaft extending upwardly in alignment with the inner portion of said access opening, and
- (d) a power unit including a casing enclosing a motor, said power unit further including a second drive shaft driven by said motor and engaging said first shaft,
- (e) said power unit being rotatable about said first drive shaft into said recess to expose a substantial portion of said access opening for permitting introduction of waste material into said hopper,
- (f) said power unit further being rotatable about said first drive shaft into registry with said access opening for driving said first drive shaft to comminute the waste material.

2. A portable waste disposer for use in a kitchen sink comprising:

- (a) a housing forming a hopper,
- (b) said housing including an upper wall defining an access opening for receiving waste material,
- (c) waste material comminuting means within said hopper including a rotatable impeller having a first drive shaft extending upwardly in alignment with said access opening,
- (d) a power unit including a motor and a second drive shaft driven by said motor,
- (e) means for hingedly mounting said power unit on said upper wall for pivotal movement of said unit into and out of registry with said access opening,
- (f) said second shaft drivingly engaging said first shaft when said power unit is in registry with said access opening to effect comminution of waste material, and
- (g) a spring-biased latching arrangement for releasably securing said power unit in registry with said access opening.

3. A portable waste disposer for use in a kitchen sink comprising:

- (a) a housing forming a hopper,
- (b) said housing including an upper wall defining an access opening for receiving waste material,
- (c) waste material comminuting means within said hopper including a rotatable impeller having a first drive shaft extending upwardly within said chamber in alignment with said access opening,
- (d) a power unit including a casing enclosing a motor, said power unit further including a second drive shaft driven by said motor and engaging said first shaft,
- (e) said power unit further including a collar mounted around said casing with a sliding fit, a hinge supporting said collar for pivotal movement on said upper wall,
- (f) said casing being longitudinally movable a predetermined distance in a first direction within said collar to disengage said second shaft from said first shaft,
- (g) said power unit then being pivotally movable in a first direction about said hinge to expose said access opening for permitting introduction of waste material into said hopper, and
- (h) said power unit being pivotally movable in a second direction about said hinge, said casing then being longitudinally movable a predetermined distance in a second direction within said collar to engage said second shaft with said first shaft to drive said first shaft to effect comminution of waste material.

4. A portable waste disposer as described in claim 3 wherein a spring-biased plunger is mounted on said upper wall and said collar includes a recess to receive said plunger for releasably securing said power unit in registry with said access opening.

5. A portable waste disposer as described in claim 3 wherein said upper wall includes a hook portion and a spring-biased latch is mounted in said casing for cooperation with said hook portion to releasably secure said power unit in registry with said access opening.

6. A portable waste disposer for use in a kitchen sink comprising:

- (a) a housing forming a hopper,
- (b) said housing including an upper wall defining an access opening for receiving waste material, said upper wall further defining a recess communicating with said access opening,
- (c) waste material comminuting means within said hopper including a rotatable impeller having a first drive shaft extending upwardly in alignment with said access opening,
- (d) a power unit including a casing enclosing a motor, said power unit further including a second drive shaft driven by said motor and engaging said first shaft,

- (e) said power unit further including a collar mounted around said casing with a sliding fit, said collar including a projecting ear having an opening therethrough, and
  - (f) a stud mounted in said upper wall and received in said opening in said ear for pivotal movement of said power unit about a vertical axis into and out of registry with said access opening,
  - (g) said casing being longitudinally movable a predetermined distance within said collar to disengage said second shaft from said first shaft, said power unit then being pivotally movable about said stud from said access opening into registry with said recess to expose said access opening for introducing waste material into said hopper,
  - (h) said power unit being pivotally movable about said stud from said recess into registry with said access opening, said casing then being longitudinally movable a predetermined distance within said collar to engage said second shaft with said first shaft to drive said first shaft for comminuting the waste material.
7. A portable waste disposer as described in claim 6

wherein a spring-biased plunger is mounted on said upper wall and said collar includes a recess to receive said plunger for releasably securing said power unit in registry with said access opening.
